UNITED STATES PATENT OFFICE.

JOHN A. SCHARWATH, OF ELIZABETH, NEW JERSEY, ASSIGNOR OF ONE-HALF TO
CURT R. BURKHARDT, OF TEANECK, NEW JERSEY.

DESIGN FOR A ROOFING-SHINGLE.

57,865.

Specification for Design.

Patented May 10, 1921.

Application filed November 5, 1918. Serial No. 261,301. Term of patent 14 years.

To all whom it may concern:

Be it known that I, JOHN A. SCHARWATH, a citizen of the United States, residing at Elizabeth, Union county, and State of New Jersey, have invented a new, original, and ornamental Design for Roofing-Shingles, as illustrated in the accompanying drawing.

Figure 1 is a perspective view, showing the upper side of the shingle.

Fig. 2 is a similar view, showing the under side.

The shield shown in Fig. 1 is not claimed as part of the ornamental design. It is part of a trademark and is covered when the slate is in use.

What I claim is:

The ornamental design for a roofing shingle substantially as shown and described.

JOHN A. SCHARWATH.
